Patented Jan. 4, 1916.

*Inventor,
Harry C. Adam.
By Bokerell & Church Atty's.*

UNITED STATES PATENT OFFICE.

HARRY C. ADAM, OF ST. LOUIS, MISSOURI.

DESIGN FOR A LIGHTING-FIXTURE.

48,358.

Specification for Design.

Patented Jan. 4, 1916.

Application filed October 1, 1915. Serial No. 53,642. Term of patent 14 years.

To all whom it may concern:

Be it known that I, HARRY C. ADAM, a citizen of the United States, residing at St. Louis, Missouri, have invented a certain new, original, and ornamental Design for Lighting-Fixtures, of which the following is a specification, reference being had to the accompanying drawing, forming part thereof.

The figure of the drawing is an eleva-

tional view of my new design for a lighting fixture.

I claim:

The ornamental design for a lighting fixture, as shown.

HARRY C. ADAM.

Witnesses:

GEORGE R. LADSON,
GEORGE BAKEWELL.
